(57) **CLAIM**

The ornamental design for a biopsy jaw, as shown and described.

DESCRIPTION

FIG. 1 is a top perspective view of the biopsy jaw.

FIG. 2 is a bottom perspective view of the biopsy jaw.

FIG. 3 is a front plan view of the biopsy jaw.

FIG. 4 is a left side view of the biopsy jaw.

FIG. 5 is a back plan view of the biopsy jaw.

FIG. 6 is a right side view of the biopsy jaw.

FIG. 7 is a top plan view of the biopsy jaw.

FIG. 8 is a bottom plan view of the biopsy jaw.

In accordance with a second embodiment of the present invention:

FIG. 9 is a top perspective view of the biopsy jaw.

FIG. 10 is a bottom perspective view of the biopsy jaw.

FIG. 11 is a front plan view of the biopsy jaw.

FIG. 12 is a left side view of the biopsy jaw.

FIG. 13 is a back plan view of the biopsy jaw.

FIG. 14 is a right side view of the biopsy jaw.

FIG. 15 is a top plan view of the biopsy jaw; and,

FIG. 16 is a bottom plan view of the biopsy jaw.
